UNITED STATES PATENT OFFICE

FRANK D. PAGLIUCHI, OF NEW YORK, N. Y.

HYDROSTATIC PUMP

Application filed December 15, 1931. Serial No. 581,254.

My present invention relates to improvements in pumps of the character as disclosed in my United States Patent No. 1,016,768 adapted for use in elevating liquids, and it has for its object primarily to provide an improved pump of this character wherein the liquid may be elevated by the expenditure of a relatively small amount of external power, the hydrostatic head of the liquid contained

10 in the discharge column being approximately balanced by the liquid contained in the working column so as to enable it to obtain the greatest efficiency in discharging the amount of liquid delivered from the discharge column at each working stroke of the pump.

Another object of the invention is to provide an improved pump of this character wherein the lower end of the discharge column is provided with branches which communicate respectively with piston surfaces of different areas on a pump element, the said branches being connected to the discharge column by means of a conduit or other appropriate union whereby the liquid passing therethrough from one of the piston surfaces will enter the discharge column to be delivered to the surface.

A further object of the invention is to provide an improved pump of this character which embodies a pair of columns, the hydrostatic head of one column slightly overbalancing that in the other column, and these columns are arranged to act alternately upon a pumping element which may be located at substantially the level of the liquid to be pumped, these columns being adapted to serve alternately, as liquid discharges and as power mediums, by means of which the pumping element is operated.

40 To these and other ends, the invention consists in certain improvement, and combinations and arrangements of parts, all as will be hereinafter more fully described, the novel features being pointed out particularly in the claims at the end of the specification.

In the accompanying drawing, I have shown a vertical section of a hydrostatic pump constructed in accordance with my present invention.

50 Hydrostatic pumps constructed in accord-

ance with the present invention are capable of use generally in elevating liquids of various kinds, it being especially useful in the elevation of liquids from relatively low points, such as mines, high buildings, wells and the like, to the level of the ground or to any other desired point. In the accompanying drawing, I have shown one embodiment of the pump as an example, it being understood that certain modifications or changes may be made therein in order that the invention may be applied to the best advantage according to the circumstances of each particular case, as in some cases the pump may be used for lifting water or liquid from the bottom of a well or mine while in other cases, it may be used for elevating water from the ground to the upper portion of buildings and, indeed, the pump is capable of use for various purposes wherein it is necessary or desirable to elevate liquid to a considerable height.

In that form of the invention shown in the present instance, the apparatus comprises generally a liquid discharge column 1 which may extend from the bottom of a well or mine to the surface of the ground or to a suitable distance above the same where it is provided with a suitable discharge, and a second liquid containing column 2, which may be of appropriate height in proportion to that of the discharge column.

Any appropriate pumping mechanism may be employed which is acted upon by the hydrostatic pressure in these two columns, a cylinder 3 being shown in the present instance having heads 4 and 5 which close the opposite ends thereof. The lower end of the column 2 leads directly through the head 4 into the space at one end of the cylinder while the head 5 is provided with a flange or the like to which is suitably attached a supplemental cylinder 6. A piston 7 is mounted to operate longitudinally within the larger cylinder and may be packed with suitable washers or rings in order to effect a fluid-tight fit between this piston and the walls of its cooperating cylinder. The piston 7 is provided with a relatively smaller rod 8 which passes through the head 5 with a fluid-tight fit, a pair of stuffing-boxes being shown

at the opposite sides of the head 5 to effect this result. This rod 8 is connected to a relatively smaller piston 9 which operates within the smaller cylinder 6. The outer or left hand 5 end of the supplemental cylinder 6 is connected to the bottom or lower portion of the discharge column by means of a three-way valve 10 which may be of any suitable construction, that shown in the present instance 10 having a rotatable plug 11 therein which is connected to an operating crank or arm 12. One side of this three-way valve is connected as previously stated to an end of the supplemental cylinder 6 while its opposite side is 15 connected by means of a fitting 13 to the bottom or lower portion of the discharge column, this three-way valve also having a port which communicates with a waste-pipe 14. The fitting 13 which connects the three- 20 way valve to the discharge column is also connected to a branch pipe 15 which leads there-to at a suitable angle, this branch pipe communicating with the discharge side of the relatively larger piston 7 through a check or 25 non-return valve 16 and the passage 17 which in the present instance is in the form of a compound curve and leads through the head 5 of the cylinder 3. This passage just de- 30 scribed and the check or non-return valve 16 permits a discharge of liquid from the larger cylinder into the discharge column, but prevents a return flow of the liquid from the discharge column into the larger cylinder. A suction pipe 18 also enters the discharge side 35 of the larger cylinder 3, it being provided with a check or non-return valve 19 whereby liquid is permitted to flow upwardly through this suction pipe into the larger cylinder during one stroke of the piston thereof, and such 40 liquid is prevented from flowing back into the suction pipe during the power stroke of the said piston.

The hydrostatic head of the liquid in the column 2 acts upon the rear side of the relatively larger piston 7, while the hydrostatic head of the liquid in the column 1 acts upon the relatively smaller piston 9 in the supplemental cylinder, and it is generally preferable to extend the discharge pipe 1 a suitable 50 distance in excess of the head of the column 2 in order that the additional hydrostatic head thus attained will act with sufficient force upon the relatively smaller piston 9 to overcome the hydrostatic pressure of the liquid in the column 2 and the friction of the pistons and thereby effect automatically the return stroke of the pumping element. The power stroke of the pumping element, however, is effected by applying external power 55 to the liquid in the column 2 whereby the hydrostatic head thereof is increased sufficiently to overbalance the hydrostatic head in the discharge column. In the present instance, a plunger 20 is shown which operates in a cylinder that is located or formed

in the upper portion of the column 2, this plunger having a central air passage 21 which upon the power stroke of the plunger is closed a check-valve 22, this check-valve however being freely opened upon the return stroke of the plunger. The purpose of providing this check-valve is to insure the presence of a body of air within the plunger and the top of the liquid contained in the column 2 so that the plunger is capable of an accelerating motion whereby a relatively high velocity is attained, the momentum of which is delivered as an impact upon the liquid in said column. This plunger may be 70 operated in any suitable way such, for instance as by means of an appropriate motor 23, that shown being in the form of a steam or fluid pressure cylinder to which motive power may be supplied from any suitable source. The upper end of the cylinder in which the plunger 20 operates is open to the atmosphere as shown in order to admit air to this plunger as may be necessary from time to time. By depressing the plunger, the liquid in the column 2 is discharged into the relatively larger cylinder 3, acting upon the relatively large area of the piston therein and forcing the pumping element to the left. The piston within the cylinder 23 in the present instance is provided with a rod 24 carrying an actuating arm 25 which is arranged to alternately engage the upper and lower stops 26 arranged on a valve-actuating rod 27, the latter being connected in a suitable way to a three-way valve 28, this three-way valve being connected to a steam or motive fluid supply pipe 29 which leads to a cylinder 30. This cylinder and its cooperating mechanism serves in the present instance as an example of a device for automatically actuating the three-way valve 10 at the proper intervals, the supply pipe 29 in this form of the invention leading into the lower portion of the cylinder 30 which cylinder contains a reciprocating piston 31 which is normally acted upon by a compression spring 32 which tends to force it outwardly, the rod 33 of this piston being suitably connected to the operating arm 12 of the three-way valve 10. The three-way valve 28 is provided with an exhaust port 34 located at an appropriate point. When the plunger 20 is depressed, as previously stated, the arm 25 connected to the piston rod of the motor will operate upon the lower stop 26 to depress the rod 27 and thereby turn the valve 28 in a direction to admit steam or motive fluid into the cylinder 30 so as to act upon the under side of the piston 31 therein. The piston 31 will be thereby operated in a direction to turn the three-way valve 10 in a direction to cut off communication between the supplemental cylinder 6 and the discharge column 1, but to establish communication between said cylinder and the waste-pipe 14. During the movement of the 75 80 85 90 95 100 105 110 115 120 125 130

pumping element to the left, the body of water previously supplied to the larger cylinder is discharged to the surface through the passage 17, check-valve 16 and the branch pipe 15 and the discharge pipe 1. As the piston 9 in the supplemental cylinder moves simultaneously with the piston in the main cylinder, the liquid contained in the supplemental cylinder will be discharged into the waste-pipe. When the pumping element has reached the limit of its power stroke, the plunger 20 is lifted, thereby relieving the excess in hydrostatic pressure in the column 2, and at the same time closing the three-way valve 28, communication between the supplemental cylinder 6 and the waste-pipe being thereby interrupted owing to the change in the position of the valve 10, and this adjustment of the valve 10 serves to establish communication between this supplemental cylinder 6 and the column 1, the liquid in this column thereby descending in order to resume its state of equilibrium due to the excess of hydrostatic head which it possesses and, in so descending, it will act upon the piston 9 in the supplemental cylinder thereby effecting automatically the return stroke of the pumping element and during this return stroke of said element, a fresh supply of liquid is introduced into the main cylinder 3 through the suction pipe, the check-valve 16 at this time cutting off communication between the discharge column and the main cylinder.

Assuming the plunger 20 to be on its ascending movement, the valve 22 therein opens, thereby releasing the compression caused by the impact of the plunger on its down stroke and at the same time the three-way valve 28 is turned in a direction to cut off the supply of steam or motive fluid through the pipe 29 to the cylinder 30, and a vent to the atmosphere is provided for the steam or motive fluid contained in said cylinder, the spring 32 acting to return the piston 31 to its former position, the three-way valve 10 being thereby returned to a position to re-establish communication between the supplemental cylinder 6 and the discharge column. This column having a greater hydrostatic head than the column 2 acts upon the piston 9 and thereby causes both pistons to return toward the right hand position, the partial vacuum formed in the rear of the relatively larger piston 7 serving to draw a fresh charge of liquid into the main cylinder through the suction pipe. When the plunger 20 reaches the end of its stroke, it automatically reverses the position of the three-way valve 28, supplying steam and motive fluid to the cylinder 30 and causing the three-way valve 10 to turn in a direction to disconnect the supplemental cylinder 6 from the discharge column and thereby allow the water contained in the supplemental cylinder to escape to the waste-pipe. During the down stroke of the plunger

20, the valve 22 closes, and the air contained in the space between it and the top of the liquid in the column 2 is compressed and acts as a cushion to the plunger. The momentum imparted by the plunger, plus the hydrostatic head of the liquid in the column 2, being in excess of the pressure in the column 1, it follows that the liquid taken into the main cylinder will be discharged to the surface through the discharge column.

Claims:

1. A hydrostatic pump comprising pipes to contain columns of liquid, a pumping element having means for connecting it to both of said pipes and also having a liquid inlet, means for producing an overbalance of hydrostatic head in the column of liquid in one pipe to produce a stroke of the pumping element and create an overbalance of hydrostatic pressure in the column of liquid in the other pipe, the latter serving as a discharge pipe, and means for permitting the liquid so overbalanced to act upon the pumping element during its return stroke and for establishing communication between said column and the pumping element during the power stroke of the latter.

2. A hydrostatic pump comprising a pair of pipes to contain columns of liquid, a pumping element embodying a liquid inlet, a piston adapted to be acted upon by the hydrostatic pressure of the column of liquid in one pipe which serves as a discharge pipe, and a piston of relatively larger surface to be acted on by the hydrostatic pressure of the column of liquid, in the other pipe, means for increasing the hydrostatic pressure of the column of liquid in the pipe which acts on the relatively larger piston, and means for establishing communication between the relatively smaller piston and its respective column to effect the return stroke of the pumping element and for interrupting said communication during the power stroke of the pumping element.

3. A hydrostatic pump comprising a pair of pipes adapted to contain hydrostatic columns of different heights, the longer column having a discharge permanently open to the atmosphere, a pumping element having a liquid inlet, a relatively small piston area to be acted on by the hydrostatic pressure in the longer column and having a relatively larger piston area to be acted on by the hydrostatic pressure in the shorter column, means for overbalancing by impact the hydrostatic pressure in the shorter column with reference to that in the longer column to effect a power stroke of the pumping element, and means for interrupting communication between the longer column and the smaller piston during such power stroke and for establishing communication between said smaller piston and its respective column to

effect the return stroke of the pumping element.

4. A hydrostatic pump comprising a pair of pipes to contain hydrostatic columns, one having a discharge, a pumping element adapted to be acted upon by the hydrostatic pressure of both columns, said element having a liquid inlet, a device capable of acting by impact upon one of said columns to produce an overbalance in hydrostatic pressure therein to cause the power stroke of the pumping element, and means for interrupting communication between the other column and the pumping element during such impact and for establishing communication between such parts subsequently thereto to effect the return stroke of the pumping element.
5. A hydrostatic pump comprising a reciprocating pumping element provided with a liquid inlet and plurality of piston surfaces, a discharge column adapted to contain a liquid and a connection provided with a branch passage which establishes communication between one of said piston surfaces and said column and having a second branch passage which leads from another piston surface on the pumping element into the branch passage first mentioned, a non-return valve for permitting a flow of liquid in one direction only through said second branch passage while the pumping element is moving in one direction, a valve operative to permit a flow of liquid from said column through the branch passage first mentioned and to act on said pumping element to produce a return stroke thereof, and means for effecting the power strokes of the pumping element.
6. A hydrostatic pump comprising a pair of cylinders of different diameters, a pumping element embodying a liquid inlet and pair of pistons connected together to operate in the respective cylinders, a discharge column to contain a liquid which is adapted to act hydrostatically on the smaller piston, a discharge pipe leading from the discharge side of said larger cylinder into said column and having a non-return valve therein, means to act on said pumping element to drive it on its power stroke and thereby effect a discharge of liquid from the larger cylinder and through said discharge pipe and into the column, and a valve controlling communication between the smaller cylinder and said column for permitting the liquid in said column to act hydrostatically on the smaller piston to effect the return stroke of the pumping element.
7. A hydrostatic pump comprising a liquid receiving and discharging cylinder having a piston to operate therein, a relatively smaller cylinder, a piston connected to the piston first mentioned and arranged to operate in the smaller cylinder, a column adapted to contain a liquid, a three-way valve for

establishing communication alternately between said column and the smaller cylinder during the reciprocating movements, a liquid discharge pipe leading from the liquid receiving and discharging cylinder into said column and provided with a non-return valve, and means for effecting the power strokes of said pistons.

8. A hydrostatic pump comprising a pair of pipes adapted to contain columns of liquid, one of said columns serving as a power medium and the pipe containing the other column being of greater height and provided with a discharge serving as a discharge medium, a pumping element having a liquid inlet and means for establishing communication between it and said columns, a three-way valve for alternately establishing communication between the pumping element and the higher of said columns to effect movements of the pumping element in one direction, and a plunger mounted in the short pipe having a relief valve and also having a body of air interposed between it and the surface of the liquid contained therein, said plunger being adapted to produce an impact upon the liquid in the shorter pipe which is transmitted to the pumping element to produce the power stroke thereof which in turn will lift the liquid contained in the discharge pipe, the falling of the liquid in the discharge pipe causing an overbalance of hydrostatic pressure in said pipe which will effect the return stroke of the pumping element.

9. A hydrostatic pump comprising a pair of pipes adapted to contain columns of liquid, one of said columns serving as a power medium, and the pipe containing the other column being of greater height and serving as a discharging means, a pumping element having means for establishing communication between it and said columns, valve means for alternately establishing communication between the pumping element and the discharge means, said pumping element having a liquid inlet provided with a return flow check-valve, a plunger mounted on the pipe having the shorter of said columns and said plunger having a relief valve, and means connected with said valve means and plunger to operate them in timed accord, the provision and arrangement being such, that upon the downward stroke of said plunger the piston element will be operated causing liquid to be discharged from said discharge means, and the column in said discharge means serving to cause the return operation of said pumping element.

10. In a hydrostatic pump, a pipe adapted to contain a column of liquid and serving as a discharge means, a pumping element having a connection establishing communication between it and said discharge means, a relief pipe, a three-way valve in communication with said connection and relief pipe,

said pumping element having a liquid inlet provided with a return flow check-valve, a second connection establishing communication between said discharge means and said pumping element and provided with a return flow check-valve, and means to operate said valve to alternately establish communication between the pumping element and the discharge means, and establish communication between the pumping element and said relief pipe, the provision and arrangement being such, that said pumping element may be operated to discharge liquid from said discharge means, and the return operation of said pumping element being caused by said column of liquid.
